(57) **CLAIM**

The ornamental design for a shower caddy, as shown and described.

DESCRIPTION

FIG. 1 is a front perspective view of a shower caddy, showing my new design;

FIG. 2 is a rear perspective view thereof;

FIG. 3 is a front elevational view thereof;

FIG. 4 is a rear elevational view thereof;

FIG. 5 is a left side view thereof, the right side view being a mirror image of FIG. 5;

FIG. 6 is a top plan view thereof; and,

FIG. 7 is a bottom plan view thereof.
